FINGER RING

Joseph Nolen, Kaneohe, Hawaii
(1139A E. Wilson, Glendale, Calif.)

Filed Oct. 23, 1962, Ser. No. 72,224

Term of patent 14 years

(Cl. D45—10)

FIG-1

FIG-2

FIG-3

FIG-5

FIG-4

FIGURE 1 is a perspective view of a finger ring showing my new design;

FIGURE 2 is a front elevation thereof;

FIGURE 3 is a bottom plan view of the same;

FIGURE 4 is a top plan view of the same; and

FIGURE 5 is an elevational view of the same as seen from the left in FIGURE 1.

I claim:

The ornamental design for a finger ring, as shown.
